UNITED STATES PATENT OFFICE.

FRIEDRICH HAIZMANN, OF STUTTGART, GERMANY.

MEANS FOR SECURING DOOR-LATCH HANDLES.

Specification of Letters Patent. Patented Jan. 23, 1912.

1,015,679.

Application filed May 11, 1911. Serial No. 626,448.

To all whom it may concern:

Be it known that I, FRIEDRICH HAIZMANN, a citizen of the German Empire, residing at Stuttgart, in the Kingdom of Wurttemberg, Germany, have invented certain new and useful Improvements in Means for Securing Door-Latch Handles; and I do hereby declare the following to be a full, clear, and exact description of the invention, such as will enable others skilled in the art to which it appertains to make and use the same.

This invention relates to a means for fixing door latch handles which is distinguished from those hitherto employed by a greatly improved and particularly effective arrangement which avoids their disadvantages.

The invention, therefore, consists in a door latch handle fastening, comprising a roll back and knob shanks made in two parts with smooth surfaces and of such a length that their ends may be mutually inserted to a sufficient extent into the neck of the opposite handle. These shanks are forced apart by means of a screw, wedge or the like and firmly pressed against the walls of the roll back and also against the walls of the neck of the handle so that the handle is prevented being pulled out accidentally. In the middle, where the two half handle shanks meet in the roll back, they are provided with slots in which the screw, wedge or the like engages in such a way that, firstly, the door handles may be adapted to any thickness of door, and, secondly, a handle can never be pulled out even if the screw or wedge should become loose.

The invention will now be more particularly described in one form of construction, as an example, in connection with the accompanying drawings, in which,

Figure 1 is a partial section of the arrangement; Fig. 2, a front view; and Fig. 3, a second position of Fig. 2.

The door-latch handle fastening consists of handles *a* which are inserted by means of their shanks *c* in the roll back *g* of the lock *b*, and with their ends mutually in the neck *d* of the handles *a*. In order to retain the shanks *c* firmly in the roll back *g*, the shanks which bear one upon the other are provided with inclined slots or notches *e* on their mutually facing edges, in which slots a screw *f* engages which is mounted in the roll back *g*. Now if this screw *f* be tightened up, the shanks *c* are forced apart in such a way that they are pressed firmly against the walls of the handle neck *d* and the roll back *g*. By means of the slots *e*, which are of suitable length, a further adjustment corresponding to all requirements is also possible (Fig. 3).

In order to be able to get at the screw *f* at any time without difficulty, the cover plate *i* of the lock *b* is provided with a hole *h* opposite the screw, through which hole it is possible to conveniently operate the screw.

I declare that what I claim is:

A door latch handle fastening, comprising the roll back the knob shanks arranged in two parts with smooth surfaces lying flat one upon the other, with their ends mutually engaging in the necks of the handles, said shanks being provided with longitudinal slots registering with each other, and a wedge screw carried by the roll back adapted to engage the slots in the shanks, whereby said screw permits longitudinal adjustment of the shanks as well as holds said shanks firmly against the sides of the neck of the handle and the roll back.

In testimony whereof I affix my signature, in presence of two witnesses.

FRIEDRICH HAIZMANN.
